UNITED STATES PATENT OFFICE.

ROBERT W. SCOTT, OF LEEDS POINT, NEW JERSEY, ASSIGNOR TO GENERAL KNIT FABRIC COMPANY, OF UTICA, NEW YORK, A CORPORATION OF NEW YORK.

RIBED KNITTED FABRIC.

No. 928,222.

Specification of Letters Patent. Patented July 13, 1909.

Application filed November 10, 1908. Serial No. 481,983.

To all whom it may concern:

Be it known that I, ROBERT W. SCOTT, a citizen of the United States, residing in Leeds Point, Atlantic county, New Jersey, have invented certain Improvements in Ribbed Knitted Fabrics, of which the following is a specification:

My invention consists of a ribbed web knitted in a novel way and possessing certain characteristics which clearly distinguish it from an ordinary ribbed web, one of such characteristics being that although the web may be light in weight and present the appearance of being knitted very slack, it possesses features of stability and resiliency not possessed by an ordinary slack-knitted ribbed web, another characteristic being a mesh construction which improves the sanitary qualities of the web and still another characteristic being the facility with which the web can be provided on one face with predominating yarn of one material and on the other face with predominating yarn of another material.

In the accompanying drawings—Figure 1 is an exaggerated view of a piece of ribbed knitted web made in accordance with my invention; Fig. 2 is a longitudinal sectional view of the essential parts of a circular, multi-feed knitting machine constructed for the production of ribbed web in accordance with my invention; Fig. 3 is a view of two sets of the cams of the cylinder cam ring of the machine displayed in a flat plane; Fig. 4 is a bottom view of part of the dial cam ring of the machine illustrating two sets of the cams with which such ring is equipped; Fig. 5 is a view of a composite cam intended for use in the cylinder cam ring of a single feed machine; Fig. 6 is a view of a composite cam with which the dial cam ring of such single feed machine may be provided, and Fig. 7 is a view similar to Fig. 1, but illustrating another form of ribbed web embodying certain features of my invention.

The distinguishing characteristic of my improved web shown in Fig. 1 is that it presents, both in the needle wales and courses, alternations of large and small stitches, each course which has large stitches α in the wales of one face having smaller stitches γ in the wales of the other face, the disposition of the large and small stitches being reversed in successive courses. This result is attained

by the use of long and short draft cams in 55 the respective cam carriers, the relation of the cams being reversed at successive yarn feeds, thus in a machine having the needles contained in a cylinder and dial, the cylinder cam ring of the machine may, at one 60 feed, have the long draft cam and the dial cam ring the short draft cam, and, at a succeeding feed, the cylinder cam ring may have the short draft cam and the dial cam ring the long draft cam.

In Fig. 2 of the drawing, 1 represents the needle cylinder of the machine which is grooved for the reception and guidance of the needles and is suitably secured to the fixed base or bed plate of the machine. Surrounding the needle cylinder is a cylindrical cam ring 3 upon whose inner face are mounted the cams for imparting reciprocating movement to the cylinder needles, said cam ring being secured to a rotatable ring 2 to 75 which power may be applied in any of the usual ways.

The needle dial 4 is mounted on a central stem or spindle 5 and is held stationary with the needle cylinder 1 either by means of 80 engaging lugs on said cylinder and dial, such for instance as shown at 6 and 7 in Fig. 2, or in any other convenient way, and above the dial is located the dial cam ring 9 upon whose under face are mounted the 85 cams whereby reciprocating movement is imparted to the needles which are radially guided in the grooved upper face of the dial, said dial cam ring being caused to rotate with the cylinder cam ring in any ordinary 90 way.

While I have selected for the purpose of illustrating my invention, a machine of that type in which the needle cylinder and dial are stationary and coöperate with a rotating cylinder cam ring and a rotating dial cam ring, it should be understood that my invention is equally applicable to that type of machine in which the cylinder cam ring and dial cam ring are the stationary elements 100 and the needle cylinder and dial rotate, or the invention is applicable to machines having straight needle beds and reciprocating cam carriers.

Both the cylinder cam ring and the dial 105 cam ring of the machine shown in Fig. 2 are provided with cams for projecting their respective needles to the clearing point, that

2

is to say to the point at which the stitch already formed upon the needle is slipped back of the latch, and with long and short retracting or draft cams. Both draft cams 5 retract the needles to the knocking-over point, that is to say to the point where the stitch previously formed upon the needle is slipped from the end of the latch and passed over the hook of the needle in order to engage the new loop of yarn drawn by the latter. The short draft cams may impart no further retracting movement to the needles, or they may retract them to a slight extent beyond the knocking-over point, depending 10 upon the desired length of the small stitches γ , the long draft cams retracting the needles to such an extent beyond the knocking-over point as may be necessary to draw the larger 15 stitches α .

20 In Fig. 3 of the drawing, the projecting cams of the cylinder cam ring are represented at 10 and the long and short draft cams at 11 and 11^a respectively, and in Fig. 4 the projecting cams of the dial cam ring are 25 represented at 12 and the long and short draft cams at 13 and 13^a, respectively. The long draft cams are preferably such as are known as "primary" draft cams, which are comparatively short and present a relatively 30 abrupt angle, and the short draft cams are, preferably, such as are termed "secondary" cams, which are longer, are curved and present a lesser angle than the primary cams. The relation of the primary and secondary 35 cams to each other is indicated by the lines a and b and the purpose of this construction is to delay the draft on the secondary needles until the primary needles have completed their draft, the yarn which is being drawn 40 from the yarn guide by the primary needles being looped over the shanks of the intervening secondary needles and these loops being drawn through the stitches upon said secondary needles after the draft of the stitches 45 upon the adjoining primary needles has been completed. In the absence of this provision, the knitting yarn would, in the fine gage machines now employed, be trapped by the closing latches of the needles and its for- 50 ward or feeding movement would thereby be restricted to such an extent as to cause it to break under the strain. In machines of relatively coarse gage, however, my invention may be practiced even although the 55 needles of the two sets draw their stitches simultaneously.

60 In a multi-feed machine, I can practice my invention by alternating the long and short draft cams in the cylinder and dial cam rings of the machine as shown, and in a single feed machine, the same result may be attained by the use of composite cams in the cylinder and dial cam rings, such for instance as represented, respectively, in 65 Figs. 5 and 6, each cam comprising a long draft or primary member 11 or 13 and a short draft or secondary member 11^a or 13^a, each adapted to act upon the needle butts, the long draft or primary member of the cam being movably mounted on the cam ring 70 so that it can be moved into operative position in knitting one course and out of operative position in order to permit the short draft or secondary member to act in knitting a succeeding course. Such composite 75 cams can also be used on the cam bars of a straight rib knitting machine, whether single or multiple feed, so that a cam which acts as a primary cam on one reciprocation of the cam bar can act as a secondary cam on the 80 reverse reciprocation.

A machine for producing my improved fabric forms the subject of my application, Serial No. 453,610, filed September 18, 1908, and the composite cams above referred to 85 form the subject of my application, Serial No. 456,362, filed October 6th, 1908.

In my improved web the eyelet holes or 90 meshes formed by the large stitches are in zigzag relation to one another, and this peculiar disposition of the meshes imparts a characteristic appearance to the web, while the fact that both faces of the web are composed in great part of the larger stitches improves the ventilating and sanitary properties of a garment made from such web. In most cases the large stitches of one face of the web will be of somewhat greater 95 amplitude than those of the other face, as shown in Fig. 1. In the commercial web the 100 smaller stitches will usually be of such size in respect to the larger stitches that the latter will, in great measure, constitute the visible face of the web, and they can be drawn so long or from such fine yarn as to 105 impart to the web an appearance of slack knitting, while at the same time the alternation of these slack stitches with the smaller or closer stitches in each face of the web will 110 impart to said web characteristics of stability and resiliency not possessed by an ordinary ribbed web having slack or loosely knitted stitches throughout, and I am therefore enabled to produce, without sacrifice of 115 such stability or resiliency, a lighter web than usual, the lesser weight of the yarn tending to economical production. This same feature of construction also enables me to produce a web having one face composed mainly of one material and the other face 120 composed mainly of another material, for instance, if one yarn feed supplies cotton yarn and the next feed supplies woolen or worsted yarn the large and dominating stitches of one face of the web will be of cotton and 125 those of the other face of wool or worsted, thus attaining, in an efficient way, results which are now but imperfectly attained by resorting to the operation known as "plating."

130

Although I have shown my invention as embodied in what is known as a one-and-one rib web, it will be evident that it is applicable as well to the knitting of webs having 5 other types of ribs and although I have shown change from large to small stitches in every other course, the same length of stitch may prevail throughout two or more successive courses, if desired, without departing 10 from the essential characteristics of my invention, thus in Fig. 7, I have illustrated the application of my invention to a three-and-three rib having large stitches in two successive courses, alternating with smaller stitches 15 in the next two courses, the disposition of the stitches being reversed in successive wales.

I claim:—

1. A ribbed knitted web having both in 20 the courses and wales, stitches of relatively large size, alternating with stitches of smaller size.

2. A ribbed knitted web having wales with alternating large and small stitches, 25 and also having, in one and the same course, stitches of relatively large size alternating with stitches of smaller size.

3. A ribbed knitted web having in wales of each face alternating large and small 30 stitches, and also having, in one and the same course, stitches of relatively large size alternating with stitches of smaller size.

4. A ribbed knitted web having, in one and the same course, stitches of relatively 35 large size alternating with stitches of smaller size, and having the disposition of the stitches reversed in successive courses.

5. A ribbed knitted web having, in one and the same course, on each face of the web, 40 relatively large stitches alternating with shorter stitches, and having the disposition of stitches reversed in successive courses.

6. A ribbed knitted web having in one and the same course on each face of the web, 45 stitches of relatively large size alternating with stitches of smaller size, the large

stitches on one face of the web being of greater amplitude than the large stitches on the other face of the web.

7. A ribbed knitted web, having in one 50 and the same course on each face of the web, stitches of relatively large size alternating with stitches of smaller size, and having the disposition of the stitches reversed in successive courses, the large stitches on one face 55 of the web being of greater amplitude than the large stitches on the other face of the web.

8. A ribbed knitted web having stitches of relatively large size alternating with stitches 60 of smaller size in single courses, and, in single courses alternating therewith, a reverse disposition of long and short stitches.

9. A ribbed knitted web having on each 65 face of the web stitches of relatively large size alternating with stitches of smaller size in single courses, and, in single courses alternating therewith, a reverse disposition of long and short stitches, the large stitches on one face of the web being of greater amplitude 70 than the large stitches on the other face of the web.

10. A ribbed knitted web having stitches of relatively large size alternating with 75 stitches of smaller size in single wales, and in single wales alternating therewith, a reverse disposition of the long and short stitches.

11. A ribbed knitted web having stitches of relatively large size alternating with 80 stitches of smaller size in single courses and single wales, and in single courses and single wales alternating therewith, a reverse disposition of the large and small stitches.

In testimony whereof, I have signed my 85 name to this specification, in the presence of two subscribing witnesses.

ROBERT W. SCOTT.
